DESIGN FOR A SHOE

Andre Perugia, Paris, France, assignor to Saks and Company, Inc., New York, N. Y., a corporation of New York

Application April 6, 1934, Serial No. 51,338

Term of patent 3½ years

To all whom it may concern:

Be it known that I, ANDRE PERUGIA, a subject of the Kingdom of Italy, residing in Paris, France, have invented a new, original, and ornamental Design for a Shoe, of which the following is a specification, reference being had to the accompanying drawing, forming part thereof.

Figure 1 is a plan view of a shoe showing my new design.

I claim:

The ornamental design for a shoe, as shown.

ANDRE PERUGIA.
